(57) **CLAIM**

The ornamental design for a makeup brush fixing connector, as shown and described.

DESCRIPTION

FIG. 1 is a top perspective view of a makeup brush fixing connector, showing my design.

FIG. 2 is a bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front view showing a state of use of the makeup brush fixing connector with an unclaimed handle.

The broken lines in the drawings depict environmental subject matter. None of the broken lines form part of the claimed design.
